[57] **CLAIM**

The ornamental design for a valve flow diffuser, as shown and described.

DESCRIPTION

FIG. 1 is a front elevational view of a valve flow diffuser, showing a typical embodiment of my new design;

FIG. 2 is a top plan view thereof;

FIG. 3 is a bottom plan view thereof;

FIG. 4 is a side elevational view thereof; and,

FIG. 5 is a perspective view thereof.

The appearance of the rear is the same as the front.

The appearance of the left side is the same as the right side of FIG. 4.
